UNITED STATES PATENT OFFICE.

JAMES R. ROBB, OF CILTON, OKLAHOMA.

WELL-PUMPING APPARATUS.

Application filed August 6, 1927. Serial No. 211,132.

This invention relates to well pumping apparatus and more particularly to apparatus for connecting together the working valve and pump rods of oil wells or deep water wells.

An important object of the invention is to produce a device of this character which will permit ready connection or disconnection of the rods and valve.

10 A further object of the invention is to produce a device of this character which may be readily and cheaply and at the same time durably constructed, which will be simple in its operation and a general improvement in 15 the art.

These and other objects I attain by the construction shown in the accompanying drawings, wherein for the purpose of illustration is shown a preferred embodiment of 20 my invention and wherein:

Figure 1 is a side elevation of pumping apparatus including a valve and rod connector constructed in accordance with my invention;

25 Figure 2 is a vertical sectional view therethrough;

Figure 3 is a vertical sectional view at right angles to the view of Figure 2;

Figure 4 is a view similar to that of Figure 2 but with the plunger in elevation;

Figure 5 is a section on the line 5—5 of Figure 4;

Figure 6 is a section on the line 6—6 of Figure 3.

35 Referring now more particularly to the drawings, the numeral 10 generally designates a coupling having in its lower end a threaded bore 11 adapted to receive the threaded pin 12 of a traveling valve, generally designated at 13. This coupling element at its upper end is exteriorly threaded, as at 14, for engagement with interior threads provided upon the lower end of a barrel 15 and has at its upper end a vertically extending 40 spindle 16 projecting into the bore 17 of the barrel. The upper end of the spindle 16 has a reduced extension 18 providing a guide pin for a ball thrust bearing 19. Between the ball thrust bearing and the upper end of the 45 coupling member, a spring 20 surrounds the stem 16, serving to constantly urge the thrust bearing 19 upwardly. This bearing fits the bore 17 of the barrel. The barrel 15 has adjacent its upper end and preferably at diametrically opposed points inwardly projecting lugs 21, these lugs preferably being ar-

ranged in vertically aligned pairs, as indicated. A plunger 22 is provided which, at its upper end, is adapted at 23 for connection with the rod line, generally designated at 24. At its lower end, the periphery of the plunger is provided with a pair of bayonet grooves, the vertical portions 25 of which are preferably aligned. Each bayonet groove has horizontal branch grooves 26 corresponding in number to the number of lugs 21, which are arranged in vertical alignment, in the present instance two of the branch grooves being provided. These branch grooves are vertically spaced apart the same distance as the lugs. Each branch groove at a point spaced from the vertical groove has an enlargement forming a cove 27 which is confined to the lower wall of the groove, so that after the lugs 21 enter the branch grooves, the plunger 22 may have a slight vertical movement. This vertical movement should be equal to the width of the branch groove.

Above its lower end, the plunger has a diametrically extending slot 28, the ends of which vertically align with the vertical portions 25 of the bayonet grooves and connected therewith by vertically extending grooves 29. Extended through the slot 28 is a U-shaped member, the arms 30 of which are downturned, and operate in the grooves 29 and the upper ends of the vertical portions 25 of the bayonet grooves. The plunger has an axial bore 31, the upper end of which extends above the upper end of the slot 28 and has seated against the upper wall thereof a spring 32, the lower end of which bears on the cross bar 33 of the U-shaped member to constantly urge the same downwardly. In the uppermost position of the U-shaped member, the lower ends of its arms 30 clear the uppermost branch groove 26 and in the lowermost position thereof, the ends of the arms close the mouth of this branch groove. Secured to the cross bar 33 of the U-shaped member is an operating stem 34, which projects downwardly through the bore 31 of the plunger and an axial opening 35 formed in the thrust bearing to engage the end of the reduced extension 18 of the stem 16 of the coupling member 10.

The operation is as follows: The working valve is screwed in the lower end of the coupling member 10, this coupling member and the barrel having been disposed in assembled relation. The plunger 22 is then inserted in the upper end of the barrel, the lugs 21 enter-

ing the vertical portions 25 of the grooves. As these lugs move upwardly in the vertical portions of the bayonet grooves, the uppermost lugs will engage the lower ends of the 5 arms 30 of the U-shaped member, forcing the same upwardly against the action of the spring 32. When the lugs are aligned with the branch grooves 26, the plunger is rotated to engage these lugs in the branch grooves 10 and as soon as the lugs leave the vertical portions of the grooves, the U-shaped member is released and moves downwardly, so that its legs close the outer ends of the upper branches 26 preventing return of the lugs 15 therethrough. The enlargements 27 are of a depth equal to the distance through which the arms 30 must move and the downward movement of the U-shaped member does not actually take place until the lugs are engaged 20 in the enlargements 27 and the plunger 22 is moved upwardly. In this assembled relation, the valve and rods may be lowered into the well. The spring 20 forcing the thrust bearing 19 against the lower end of the plunger 22 constantly urges this plunger upwardly, so that the lugs are maintained seated in the enlargements against any ordinary stress or resistance provided by the working valve.

When it is desired that the working valve 30 be released to permit withdrawal of the rods, this is accomplished by lowering the rods until the lower end of the working valve comes to rest upon the usual standing valve or lower end of its barrel (not herein 35 closed) at which time, the weight of the rods will be placed upon the plunger 22, forcing the same downwardly against the action of the spring 20. At this time, the thrust bearing 19 is seated upon the upper end of the 40 stem 16 and supports the weight of the rods to avoid unnecessary friction. During the downward movement, the operating stem 34 engaging against the reduced extension 18 of the stem 16 is forced upwardly against 45 the action of the spring 32, moving the U-shaped member upwardly, so that the lower ends of its arms clear the upper branch groove and the plunger may be rotated to bring the lugs 21 and vertical portions 25 of 50 the bayonet grooves into alignment. When aligned in this manner, the plunger 22 may, of course, be withdrawn, leaving the barrel 15 and coupling member 10 attached to the valve. It will, of course, be obvious that 55 coupling may be had by reversing this operation. To assist in guiding the plunger 22 into the bore 17 of the barrel 15, the lower end of the plunger is slightly rounded or tapered, as indicated at 36.

60 It will be obvious that by use of a device of this character a ready coupling of the valve and rods may be obtained and at the same time accidental disconnection of these elements is avoided. It is pointed out that 65 by use of a device of this character, the opera-

tor is enabled to connect the rods after the working barrel and tubing have been installed, thus enabling use of a working barrel which is of considerably greater size than the tubing. Under these circumstances, it will 70 be obvious that the working barrel would have to be placed in the barrel at the time the tubing was run and without the use of a device of this character, it would be necessary that the tubing and rods be run simultaneously which would, of course, be extremely 75 difficult. It will also be obvious that the structure disclosed is capable of a certain range of change and modification without materially departing from the spirit of the invention and I accordingly do not limit myself to such specific structure except as hereinafter claimed.

I claim:

1. In combination, a barrel, a plunger in 85 the bore of the barrel, the barrel in its bore having a lug and the plunger having a bayonet groove for the reception of the lug, a member longitudinally shiftable on the plunger in the vertical branch of the groove 90 and yieldable means exerting pressure on said member, said member obstructing the circumferential branch of the groove, said lug being of less axial length than at least a portion of said circumferential branch of the groove 95 whereby the barrel and plunger may have relative longitudinal movement, a spring normally holding the barrel and plunger at one limit of said movement, and means withdrawing the member from its obstructing position 100 in the groove as the barrel and plunger are shifted to the opposite limit of said movement against the action of the spring.

2. In combination, a barrel, a plunger in 105 the bore of the barrel, the barrel in its bore having a lug and the plunger having a bayonet groove for the reception of the lug, a member longitudinally shiftable on the plunger in the vertical branch of the groove and yieldable means exerting pressure on said member, 110 said member obstructing the circumferential branch of the groove, said lug being of less axial length than at least a portion of said circumferential branch of the groove whereby the barrel and plunger may have relative 115 longitudinal movement, a spring normally holding the barrel and plunger at one limit of said movement, means withdrawing the member from its obstructing position in the groove as the barrel and plunger are shifted to the opposite limit of said movement against the 120 action of the spring, and a thrust element interposed between the spring and plunger upon which the plunger seats when at the last named limit of its movement.

3. In combination, a barrel, a plunger in 125 the bore of the barrel, the barrel in its bore having a lug and the plunger having a bayonet groove for the reception of the lug, a member longitudinally shiftable on the 130

plunger in the vertical branch of the groove and yieldable means exerting pressure on said member, said member obstructing the circumferential branch of the groove, said 5 lug being of less axial length than at least a portion of said circumferential branch of the groove whereby the barrel and plunger may have relative longitudinal movement, a spring normally holding the barrel and 10 plunger at one limit of said movement, said

member having an operating stem coming into operative engagement with the barrel as the barrel and plunger are shifted to the opposite limit of said movement against the action of said spring to thereby withdraw the 15 member and enable movement of the lug into the vertical branch of the groove.

In testimony whereof I hereunto affix my signature.

JAMES R. ROBB.
